UNITED STATES PATENT OFFICE.

WILLIAM FORD SCHMOELE, OF ANTWERP, BELGIUM, ASSIGNOR TO JULIA MULLENDERS, OF ANTWERP, BELGIUM.

AIR-COOLED CYLINDER AND PISTON CONSTRUCTION FOR HIGH-HEAT EXPLOSION-MOTORS.

1,315,686.

Specification of Letters Patent.

Patented Sept. 9, 1919.

Application filed January 10, 1914. Serial No. 811,329.

To all whom it may concern:

Be it known that I, WILLIAM FORD SCHMOELE, a citizen of the United States, residing in Antwerp, in the Province of 5 Antwerp and Kingdom of Belgium, have invented a new and useful Air-Cooled Cylinder and Piston Construction for High-Heat Explosion-Motors, of which the following is a specification.

- 10 The object of this invention is to produce, for air-cooled explosion motors, a construction of cylinder, piston and piston guide tolerating heat enough to use, without smoke or soot, such liquid fuels as cannot be 15 volatilized, nor remain volatilized, under 250 degrees centigrade, and which do not explode under this temperature. Examples of these are the petroleum oils such as lamp oil and heavier, also mazout and shale oils, 20 and sundry vegetable oils extracted from pitch and the like; as also mineral oils distilled from coal tar and the like.

It is well known that ordinary air-cooled, ribbed cylinders, without water cooling, do 25 not allow of a strong compression of their charges because their lubricant, being overheated, would become too thin and be blown out or evaporated, if indeed the cylinder escaped gripping. On the other hand those 30 chilled by water cannot use as fuel the heavy oils of high volatilization temperature, because these, during the aspiration would deposit as dew on the too cool walls; and this dew, being liquid, does not explode, but 35 rather burns forming smoke and soot. My invention obviates the difficulty by allowing the cylinder and piston to heat up to a point at which a dew of condensation cannot form, while at the same time preventing the high 40 temperature from hurting these two organs.

Figure 1 shows a section through the median line of the cylinder and contents, as seen from in front.

Fig. 2 a like section, but seen from the 45 side.

Fig. 3 is a cut in the line 3, 3 of Fig. 1.

My motor needs only air cooling by ribs and fan, and tolerates heat high enough to prevent fuel condensation, and without hurt 50 to its lubrication, by reason of its double-length divided cylinder, formed of an upper part A and a lower part B separated by a heat insulating joint C. Its walls are

simple, and have no metallic lining; its head is as good a conductor of heat as possible, 55 additional cooling surfaces being added in the shape of ears a a ribbed on both sides. The mass of these ears is very thick where they grow out from the cylinder body, so as there to conduct a great quantity of heat, 60 and the mass lessens progressively in thickness at each rib proportionally to the quantity of heat diverted at each rib or there conducted away.

The piston is made of a single tube of 65 steel, and as thin as consistent with strength, so as to oppose the least resistance to the free passage of heat from its outside surface facing the explosions to its inside surface facing the ventilating air current within. 70 Besides this the connection between the piston head and the top of the pitman is made of great length so that but little heat can be connected to the pitman's head, which must remain cool to preserve its full hard 75 temper. For this purpose a long shaft K K is provided, preferably of Greek cross section, so as to give great stiffness with but little metal; and this shaft is perforated with numerous holes both to reduce weight 80 and to bar heat connection through the metal. The end of this shaft K K farthest from the piston head is connected with a cylindrical sheath J J, preferably of bronze or other metal not gripping with iron, and 85 the sheath J J receives the slant thrusts of the pitman and communicates them to the inner face G G of a guide mechanism G g hereafter described, and situated within the piston. 90

The guide is composed of an inner continuous cylindrical tube g surrounded by an outer tube G concentric with it and leaving space between them wherin to canalize an air current. These two concentric tubes g 95 and G are cast together in one piece with a partition wall h joining them at each side 180 degrees apart, thus forming two semi-circular grooves H, through one of which near the bottom on one side the air current 100 enters, thence rises to the very top of the guide, crossing which it descends through the other groove and passes out at the other side near the bottom. When the piston is down the inner surface of its head is very 105 near to the top of the guide, so that the

air current sweeping across from one groove to the other comes into close contact with the hot metal of the piston head.

The inner tube *g* forms also a gliding race for the sheath *J J* on the shaft *K K*, and withstands the slant thrusts of the pitman as aforesaid. Thus a single and continuous cylindrical surface *g g*, surrounding a like cylindrical sheath *J J* fitting snugly into it, forms an air-tight race, which prevents the oily fog engendered in the crank box from finding its way into the ventilating stream of air continually sweeping through the piston and its guide. The contact of such a fog with a piston head so hot as mine would, by the gasification of its globules, form at once an opaque and malodorous smoke, which would be blown out into the atmosphere as a bluish-gray cloud.

The lubrication of the piston is effected in two places; namely on the central sheath *J J* and on the piston rings. Both of these are afar off from the hot head of the piston, hence distance protects them from its heat.

The sheath *J J* is oiled at each descent by the direct splash from the crank box; but the rings cannot be so reached and are lubricated as follows. The floor of the guide piece forms a shallow depression or pool *P* to hold oil *M*. Above the pool a tube leads to a cavity formed higher than the floor and in the direction whither the pitman splashes the oil in the crank box. The oil thus thrown up into the cavity flows down through a tube into the pool, whose depth is controlled by an overflow pipe *N*, threaded externally and opening downward into the crank box. The piston rings do not plunge into this pool; their lubrication thus would be excessive. The lowest ring carries a number of points *Q*, preferably triangular in shape with the apex downward, and these plunge into the oil at each descent, gathering each a small drop, just as much as will

stick to their apex. This dose being continually repeated is enough; more would be too much.

Having now particularly described and ascertained the nature of my said invention, and in what manner the same is to be performed, I declare that what I claim is:

1. In an explosion motor of the air-cooled type, a cylinder formed in two sections provided with fins, and a hollow trunk piston reciprocating therein, having sealing means only at its lower end, the upper section providing space for the combustion chamber and the upper portion of the piston when at the top of its stroke, the lower section forming a raceway for the portion of the piston carrying the sealing means, a heat insulating joint between the sections, a hollow cylindrical piston rod rigidly secured within the piston, and having ventilating apertures therethrough, a pitman connected to said piston rod and a stationary cylindrical guide surrounding the piston rod, having passages therethrough which coöperate with said ventilating apertures to form a conduit for the passage of cooling fluid, substantially as described.

2. In an explosion motor a crank case, a fluid-cooled hollow piston having a hollow cylindrical piston rod projecting centrally within the hollow portion, closed at its lower end with ventilating apertures in its upper portion, a cylindrical guide in which the piston reciprocates, forming an oil-tight joint between the interior of the piston and the crank case, the walls of said guide being hollow and inclosing two semi-annular passages coöperating with said ventilating apertures to form a conduit for cooling fluid, substantially as set forth.

WILLIAM FORD SCHMOELE.
